(57) **CLAIM**

The ornamental design for a water proof water sensor, as shown and described.

DESCRIPTION

FIG. 1 is a left facing isometric view of the water proof water sensor showing our new design;

FIG. 2 is left view thereof;

FIG. 3 is a right view thereof;

FIG. 4 is a back view thereof;

FIG. 5 is a front view thereof;

FIG. 6 is a top view thereof; and,

FIG. 7 is a bottom view thereof.

The broken lines depict portions of the water proof water sensor that form no part of the claimed design.
